[57] CLAIM

The ornamental design for a sight for an archery bow, as shown and described.

DESCRIPTION

FIG. 1 is a perspective view of a sight for an archery bow showing my new design;

FIG. 2 is a side elevational view thereof;

FIG. 3 is an end elevational view illustrating one end thereof, the other end being a mirror image thereof;

FIG. 4 is a top plan view thereof the bottom plan view being a mirror image thereof;

FIG. 5 is a side elevational view thereof illustrating the side opposite that illustrated in FIG. 2.

The broken line showing of threading rods, in FIG. 1, is for illustrative purposes only and forms no part of the claimed design.
